JET-REACTION MOTOR, INCLUDING GAS
NOZZLE GENERATING STEAMHelmut Alfredo Arturo Exner, Florida,
ArgentinaApplication September 15, 1947, Serial No. 774,046
In Argentina March 29, 1947

2 Claims. (Cl. 69—35.6)

1

The present invention relates to jet propulsion motors and has for a main object improvements over other known types of motor and consisting in the provision of means conducting the combustion and evaporation products from a stator chamber housing the rotor to an expulsion conduit.

The most modern motor of that type is at present the "Derwent" of Rolls-Royce; yet its outstanding disadvantage is the loss of about two-thirds of the total power generated, being lost in the ventilator or turbine system in an effort to compress the air prior to combustion.

According to the present invention the centrifugal force developed by the rotor of the motor is utilized in compressing the air prior to combustion and the conventional turbine driving the rotor is dispensed with since the burnt gases by their reaction on jets emitting them drive the rotor at high speed.

By conducting these gases through jets of a certain direction and sense, unequalled speed is attained with a fuel consumption far lower than that of known motors.

Other objects will become apparent after reading the following description.

To fully understand the invention, the description should be read in connection with the accompanying drawings forming part of the application and illustrating the invention by means of an example rather than by a limitation and wherein:

Figure 1 is a fragmentary section of the jet propulsion motor constituting the preferred embodiment of my invention;

Figure 2 is a section at right angles to the section of Figure 1;

Figure 3 is a top plan view of a modification of two motors including two stator chambers;

Figure 4 is an elevation partly in section of the modification.

In the drawings, in which like characters of reference designate like or similar parts, Figures 1 and 2 illustrate a motor comprising a rotor divided by radial partitions into a plurality of sectoral air chambers 2 each communicating with a precombustion air heating chamber 3 arranged at the periphery of an air chamber by an opening 4.

The rotor includes a shaft 5 having two axial conduits 6 and 7 communicating with a plurality of radial conduits 8 and 9, respectively. Each conduit 8 is connected to an atomizer or injection nozzle 10 atomizing the fluid fuel while conduit 9 conducts water or other non-combustible liquid.

2

Nozzle 10 has an opening 12 whereby it communicates with a combustion chamber 13 housing an ignition rod 15 opposite opening 12 and in turn communicating with the precombustion chamber 3 by an aperture 14.

The gases burned by ignition rod 15 are expelled through an opening 16 after having passed through a plurality of pipes 17 extending through a vaporization chamber 11 which communicates at one end with the outside by a nozzle 18 terminating in an outwardly expanding cone 19 and is supplied at the other end with water by conduit 9.

Cones 18 and openings 6 are arranged on the periphery of the rotor and the steam and products of combustion respectively expelled therefrom impinge against blades or vanes 20 fixed in an annular chamber of stator 21 which is open at its inner periphery and rigid with bearings for motor shaft 5 and receive a part of the outer periphery of the rotor. The steam is then condensed in a condensing means guided by channel means 22.

Air for combustion is supplied to chambers 2 by central openings 23 concentric with shaft 5 and while the motor is rotating at about 500 revolutions per minute, is impelled by centrifugal force through openings 4 into precombustion chambers 3 and thence through openings 14 into combustion chambers 13. The mixture of compressed air and atomized fuel is ignited by rod 15 and hurled against stator blades 21.

Opening of valve 25 causes inoculation of the non-combustible liquid through conduits 7 and 9 to chamber 11 where the liquid is vaporized by contact with tubes 17 conducting the burnt gases.

The high pressure steam leaving through nozzle 18 out cones 19 is hurled against blades 20 of stator 21 and is then conducted through conduit 22 to a suitable condenser.

Figures 3 and 4 illustrate a modification applying the motor to an aircraft by providing a housing 26 with an internal spirally-shaped surface and communicating with the outside through expulsion conduit 27.

Housing 26 functions as a stator of a motor the rotor of which is spaced from the internal housing surface to form a channel 29 having a cross section increasing toward conduit 27 through which the gases leave as a high powered jet.

In order to lower the temperature of the heat produced in the combustion chambers and conduit 29, the formers are used only during the time the craft is airborne or in cases of emer-

gency. Under normal conditions the atomizers work alternatively, the supply of fuel to the idle atomizers being shut-off, but since air will circulate through all openings 23, the temperature within conduit 29 will be lowered.

In the embodiment illustrated in Figures 3 and 4, the motor operates exclusively by means of the products of combustion, therefore no evaporation chambers are provided, the displacement of the aircraft being effected by the reaction of the gas at the outer end of conduit 27.

The same may be provided with an outlet opening in a direction opposite to the direction of that causing the displacement of the aircraft in order that the products of combustion may be utilized to exert a braking effect.

I claim:

1. In a jet-reaction motor, the combination, comprising, an annular stator housing open on its inner periphery, a pair of bearings fixed to the stator housing, a shaft journaled in the bearings, a hollow rotor fixed to the shaft and extending into the inner periphery of the stator and having an air inlet adjacent the shaft, a plurality of angularly spaced air heating chambers in the rotor adjacent the periphery thereof and supplied with air entering through the inlet by the rotation of the rotor, a plurality of combustion chambers one in each air heating chamber and having an air intake communicating therewith, a plurality of ignition means one in each combustion chamber and disposed in a plane at right angles to the rotor axis, said plane also containing the corresponding intake, a plurality of atomizers one in each combustion chamber and disposed in said plane and on the side of the corresponding ignition means oppo-

site the corresponding air intake, a plurality of spaced vaporization chambers in the rotor adjacent the periphery thereof, a plurality of radial water conduit means each supplying one of the vaporization chambers with water by the rotation of the rotor and one for each combustion chamber, and a plurality of other conduit means at least one for each of the vaporization chamber means and conducting the burnt gases from a combustion chamber through the corresponding vaporization chamber, substantial tangential outlets each connected to a vaporization chamber, and separate substantial tangential outlets for the other conduit means.

2. The combination according to claim 1 and also comprising a pair of axial conduits formed in the shaft one supplying air and the other supplying water to the water conduit means, and radial air conduits each connecting the axial air conduit with an atomizer.

HELLMUTH ALFREDO ARTURO EXNER.
